ADVERTISING DEVICE

Philo R. King, Webster Groves, Mo., assignor to
 Union Starch & Refining Company, Columbus,
 Ind., a corporation

Application May 4, 1934, Serial No. 723,946

11 Claims. (Cl. 40—126)

This invention relates to means for displaying packed goods particularly canned goods and has for a primary purpose the provision of means whereby containers of varying sizes may be telescoped together for convenience in transportation and then opened up in extended relation so as to display the varying sizes of containers with their standard exterior finishes and/or labels thereon all without damage thereto.

10 The invention is particularly adapted to cans or buckets which may be employed to contain particular lines of goods, the particular line herein referred to being syrup. One particular advantage of the invention is found by salesmen of the goods in that instead of having to carry a number of separate cans to show the line of goods in the different sized packages, the salesman may carry a single unit which has exterior dimensions equalling that of the largest size container in the line. Then when the containers are to be displayed, the salesman may lift the innermost container and withdraw it to in turn withdraw the other sizes of containers until all are fully extended and then displayed to the prospective customer. When the exhibition is over, the containers may then be pushed together all to telescope within the larger carrying container. The containers may each individually be provided with some distinguishing finish or equipped with 20 a label indicating the contents ordinarily carried in that size of container. Of course it is advisable to keep the exteriors of the containers in a neat, clean condition without scratches or other blemishes appearing thereon. It is equally within the 25 province of this invention to have the containers finished in some peculiar style with the finish applied thereto in any manner, or to have a label attached to the container. An essential feature is that whatever form the distinguishing characteristics assume, they be protected against damage by one container rubbing over the other. This condition is difficult to maintain when the containers are dropped loosely one within another and even when the containers are carried separately or moved one from another.

Other objects and advantages of the invention will become apparent to those versed in the art in the following description of one particular form of the invention which is made in reference to the accompanying drawings, in which

Fig. 1 is a top plan view of a structure embodying my invention;

Fig. 2, a side elevation on a reduced scale of a series of containers in an extended display position;

Fig. 3, a central vertical section through the structure in the telescoped relation;

Fig. 4, a central vertical section through the structure on a plane revolved 90° from that of the section shown in Fig. 3;

Fig. 5, a transverse horizontal section on the line 5—5 in Fig. 4, and

Fig. 6, a bottom plan view.

Like characters of reference indicate like parts throughout the several views in the drawings.

In the particular form of the invention herein shown and described, the line of goods to be displayed happens to have a series of containers varying in size and five in number ranging from a small size through graduations up to the larger size. For the sake of convenience, the containers will be referred to as metallic containers adapted to hold syrup. The syrup is, for example, of five different types, one type being distinguished from the other by the size of the container and by the designation appearing thereon. The varying types are designated, Fig. 2, as A, B, C, D, and E, the letters being merely arbitrarily selected for the purpose of describing the invention rather than relating to the actual identification of the types of syrup.

Starting with the smallest container which would hold syrup A, this container is designated by the number 10 and is provided with a central tube 11 fixed within the container centrally of the bottom thereof to extend upwardly therefrom for a distance less than the total height of the container. The bottom of the container 10 is cut through so as to have an opening not less than the internal diameter of the tube 11. The container 10 is provided with the usual friction type lid 12 which has a hinged handle 13 secured thereto. The lid 12 is preferably fixed to the container 10 by some such means as soldering.

Now the next larger size container 14 has its cover removed and discarded and is fitted with a tube 15 secured centrally to the bottom of the container to extend upwardly therein and to have an external diameter which will slidably fit within the tube 11 when the container 10 is placed within the container 14 by its lower end. To the under side of the container 10 is fixed a bracket 16 to have a portion thereof extending downwardly to carry a band of metal 17 which is curved to fit within and bear frictionally against the wall of the container 14. The vertical height of this band 17 is made to be such that when the upper side of the container 10 is flush with the top of the container 14, the lower edge of the band 17 bears against the bottom of the con-

tainer 14 to serve as a stop. This band 17 is split as at 18, Fig. 4, so that it may be sprung together to reduce its diameter temporarily while it is being inserted through the open end of the container 14, following which the band may expand to spring against the wall of the container 14. Not only does the band 17 serve as a stop to limit downward travel of the container 10 in respect to the container 14 but it also serves as a stop to prevent complete withdrawal of the container 10 therefrom and further serves as a frictional engagement with the container 14 so as to hold the container 10 at the desired degree of elevation.

15 The next larger size container 45 containing the syrup C will receive the container 14 therewithin. The container 45 is provided with a plurality of vertically disposed guides 19, here shown as three in number, and each being substantially U-shape in cross section. Attached to the under side of the container 14 are shoes 20, here shown as three in number, one to fit over each of the guides 19. These shoes 20 are secured to the under side of the container 14 and extend downwardly therefrom to fit along the guides and in fact as shown in Fig. 4 extend through cut-outs in the bottom of the container 45, Figs. 3 and 4. One of these shoes 20 is fitted with a horizontally disposed tubular extension 21, Fig. 4, within which is carried a spring 22 urging a ball 23 against the guide 19. When the container 14 is pulled upwardly from out of the container 45, the upper edges of the shoes 20 will strike against the under side of and be stopped by the flange 24 on the top end of the container 45, the container 14 then being positioned to have its under side substantially in the plane of the top side of the container 45, Fig. 2. That guide 19 against which the ball 23 is pressed has an indentation 25 into which the ball 23 may drop when the container 14 is moved to its uppermost position so as to yieldingly retain the container 14 in its extended or uppermost position.

15 The next larger container 46 is of that size which will receive therein the container 45. The container 46 is provided with a plurality of vertically disposed guides 26, here shown as three in number, extending along the inner side of the vertical wall of the container. The container 45 carries by its lower end a plurality of shoes 27, one fitting over each of the guides 26. The guides 19 carried by the container 45 extend through the bottom of the container 45 for a sufficient distance to bear against the bottom of the container 46 when the upper end of the container 45 is flush with that of the container 46. One of the shoes 27 carries a tubular extension 28 within which is carried a compression spring 29 urging a ball 30 against the guide 26 so that when 60 the container 45 is in its uppermost position which is determined by the shoes 27 striking against the inturned flange about the top of the container 46, the ball 30 will drop into the indentation 31 and thereby yieldingly retain the container 45 in its extended position above the container 46.

70 In like manner the largest container 47 is provided with a plurality of vertically disposed guides 32, here shown as three in number fixed to the inner side of the wall of the container. The under side of the container 46 carries shoes 33 one to fit about each of the guides 32. One of these shoes 33 carries a tubular extension 34 within which is a compression spring 35 urging a ball 36 against the guide 32 so that when the container

46 is withdrawn from the container 47 and lifted to its uppermost position as determined by the top edges of the shoes 33 striking the inturned flange 37 of the container 47, the ball 36 will drop into the indentation 38 on the guide 32 and thereby 5 yieldingly retain the container 46 in its elevated position.

10 The bottom of the container 47 is cut away to permit assembly of the units as above indicated and is then closed by the cap 39 which is preferably fixed in place by some such means as brazing or soldering. To provide clearance for the extension 34, the cap 39 is notched out to have an inwardly extending portion 40, Figs. 3 and 6. Preferably a bar 41 extends diametrically across 15 between the side walls of the cap 39 to provide a hand grip so as to hold the container 47 when the handle 13 of the container 10 is gripped and pulled to withdraw the various containers 10, 14, 45, and 46 from the container 47.

20 The various shoes carried by the containers 14, 45 and 46 are so shaped and proportioned and attached to the respective containers that the containers are spaced radially one from the other to provide clearance as the containers are withdrawn one from another. The spring band 17 is employed in place of guides and shoes as between other containers for the reason that the container 10 very closely approaches the size of the container 14 so as to make it difficult to assemble guides 30 and shoes between the two containers.

25 Thus it is to be seen that as illustrated in Fig. 2, the various sized containers may be displayed stacked in effect one on the other to give a visual indication not only of the various finishes or labels designating the type and quality of the goods in the respective containers but there is also at once a visual indication of the relative sizes of those containers. When the display is completed, the container 10 may be pushed downwardly so 40 as to in turn push the other containers all down until all are nested within the container 47. The container 47 may then be carried about by the usual handle 42. By use of my invention, all of the varying sized containers may be carried about 45 conveniently without taking up any more space than the largest one in the group.

30 While I have herein shown and described my invention in the one particular form, it is obvious that structural changes may be made without departing from the spirit of the invention and I, therefore, do not desire to be limited to that precise form beyond the limitations as may be imposed by the following claims.

35 I claim:

1. A device for displaying a plurality of varying sizes of containers with distinguishing characteristics thereon comprising in combination, means slidably guiding a container telescopically one within the other, said means being formed to space one container transversely from the other to protect said characteristics carried thereon, and stops limiting the extended positions of the containers to have the bottom of an upper container not higher than the top of the next lower container and means for releasably retaining the containers in extended position.

2. A device for displaying a plurality of varying sizes of containers carrying distinguishing characteristics thereon comprising in combination, 70 means slidably guiding a container telescopically one within the other, said means being formed to space one container transversely from the other to protect said characteristics, and stops limiting the extended positions of the containers to have 75

the bottom of an upper container not higher than the top of the next lower container, and means yieldingly retaining the containers in extended positions.

5 3. For indicating a line of goods packed in various sizes of containers each having a distinctive characteristic, a plurality of standard containers, the largest of which is selected as a receptacle within which the other containers are nested for convenience in saving of space for transportation, guides fixed to the inner walls of at least the larger of said containers, shoes carried by the inner containers to slidably engage those guides and centrally space successively each smaller container from its surrounding larger container so as to hold the characteristics on the containers out of contact with the surrounding containers, and means yieldingly retaining the containers in extended positions when shifted upwardly one out 20 of the other.

4. For indicating a line of goods packed in various sizes of containers having distinctive characteristics, a plurality of standard containers, the largest of which is selected as a receptacle within 25 which the other containers are nested for convenience in saving of space for transportation, guides fixed to the inner walls of at least the larger of said containers, shoes carried by the inner containers to slidably engage those guides and centrally space successively each smaller container from its surrounding larger container so as to hold the characteristics on the containers out of contact with the surrounding containers, and means yieldingly retaining the containers in 30 extended positions when shifted upwardly one out of the other, and means spacing one container vertically within the other to have the tops of all containers in the same plane when fully nested.

5. For indicating a line of goods packed in various sizes of containers having distinctive characteristics, a plurality of standard containers, the largest of which is selected as a receptacle within 40 which the other containers are nested for convenience in saving of space for transportation, guides fixed to the inner walls of at least the larger of said containers, shoes carried by the inner containers to slidably engage those guides and centrally space successively each smaller container from its surrounding larger container so as to hold the characteristics on the containers out of contact with the surrounding containers, and means yieldingly retaining the containers in 45 extended positions when shifted upwardly one out of the other, a lid carried by the innermost and smallest container, a handle fixed to the lid, a cupped insert in the bottom of the largest container, and a handle carried within the insert.

6. For indicating a line of goods packed in various sizes of containers having distinctive characteristics, a plurality of standard containers, the largest of which is selected as a receptacle within 50 which the other containers are nested for convenience in saving of space for transportation, guides fixed to the inner walls of at least the larger of said containers, shoes carried by the inner containers to slidably engage those guides and centrally space successively each smaller container from its surrounding larger container so as to hold the characteristics on the containers 55 out of contact with the surrounding containers, and means yieldingly retaining the containers in extended positions when shifted upwardly one out of the other, and means spacing one container vertically within the other to have the tops of all containers in the same plane when fully nested,

a lid carried by the innermost and smallest container, a handle fixed to the lid, a cupped insert in the bottom of the largest container, and a handle carried within the insert.

7. For indicating a line of goods packed in various sizes of containers each having a distinctive characteristic denoting the contents to be carried in the particular size of container, a plurality of standard containers, the largest of which is selected as a receptacle within which the other containers may be nested to save space in transportation, vertical guides fixed to the inner walls of at least the larger of said containers, shoes carried by the inner containers of the larger sizes to slidably engage those guides and centrally space the successively smaller container from its surrounding larger container to protect the characteristics on the outer sides of the containers, tubes fixed to the containers having less clearance between adjacent containers than said larger containers, said tubes slidably telescoping to space apart centrally those tube carrying containers, and stop means limiting the withdrawal of one container from the other.

8. For indicating a line of goods packed in various sizes of containers each having a distinctive characteristic denoting the contents to be carried in the particular size of container, a plurality of standard containers, the largest of which is selected as a receptacle within which the other containers may be nested to save space in transportation, vertical guides fixed to the inner walls of at least the larger of said containers, shoes carried by the inner containers of the larger sizes to slidably engage those guides and centrally space the successively smaller container from its surrounding larger container to protect the characteristics on the outer sides of the containers, tubes fixed to the containers having less clearance between adjacent containers than said larger containers, said tubes slidably telescoping to space apart centrally those tube carrying containers, and stop means limiting the withdrawal of one container from the other, and yielding means retaining the containers in extended positions.

9. For indicating a line of goods packed in various sizes of containers each having a distinctive characteristic denoting the contents to be carried in the particular size of container, a plurality of standard containers, the largest of which is selected as a receptacle within which the other containers may be nested to save space in transportation, vertical guides fixed to the inner walls of at least the larger of said containers, shoes carried by the inner containers of the larger sizes to slidably engage those guides and centrally space the successively smaller container from its surrounding larger container to protect the characteristics on the outer sides of the containers, tubes fixed to the containers having less clearance between adjacent containers than said larger containers, said tubes slidably telescoping to space apart centrally those tube carrying containers, and stop means limiting the withdrawal of one container from the other, and yielding means retaining the containers in extended positions, and spacing means holding said containers when nested to have their upper ends in a common plane.

10. That method of assembling a plurality of varying sizes of containers of a line of goods into a telescoping unit for displaying characteristics of the containers to give a visual indication of the comparative sizes of containers under the

various characteristics which consists in affixing spacing means between the smallest and the next larger or second of the containers, placing guides in the next larger or third container, inserting the first two containers within the third container, affixing shoes to the bottom of the second container through the bottom of the third container to engage the slides in the third container to space the second container therefrom, placing guides in the next larger or fourth container, then affixing shoes to the bottom of the third container through the bottom of the fourth container, and so on until all of the containers have been so assembled.

11. A telescoping display unit for visually indicating a line of goods embodying in combination a series of goods containers arranged in sequence as to size from the largest to the smallest one above the other and with respective designations thereon to indicate the relative sizes of the containers in respect to the goods to be carried therein, and means transversely spacing apart one container from the other when in nested positions so as to protect said designations. 5 10

PHILO R. KING.
